(57) **CLAIM**

The ornamental design for a stator for a vehicle alternator, as shown and described.

DESCRIPTION

FIG. 1 is a front view of a stator of a vehicle alternator according to a first embodiment;

FIG. 2 is a plan view thereof;

FIG. 3 is a rear view thereof;

FIG. 4 is a bottom view thereof;

FIG. 5 is a right side view thereof;

FIG. 6 is a left side view thereof;

FIG. 7 is a perspective view thereof;

FIG. 8 is a front view of a main part of a stator according to a second embodiment; and,

FIG. 9 is a perspective view of a main part of the stator illustrated in FIG. 8.

The broken line showing is included for the purpose of illustrating the stator and forms no part of the claimed design.

The product related to this design is a stator of an alternator for a vehicle composed of a stator core and coils. As an embodiment, a rotor is rotatably supported in the inner periphery of the product fixed to a housing of the alternator.
